AUTOMATIC WATER ELEVATING APPARATUS

Filed March 2, 1921

UNITED STATES PATENT OFFICE.

JAMES D. FOSTER, OF TUSCALOOSA, ALABAMA.

AUTOMATIC WATER-ELEVATING APPARATUS.

Application filed March 2, 1921. Serial No. 449,117.

To all whom it may concern:

Be it known that I, JAMES D. FOSTER, a citizen of the United States, residing at Tuscaloosa, in the county of Tuscaloosa and 5 State of Alabama, have invented certain new and useful Improvements in Automatic Water-Elevating Apparatus, of which the following is a specification, reference being had to the accompanying drawings.

10 It is an object of the present invention to provide an apparatus of this character, for automatically elevating water or other liquid from wells, sumps, lakes, springs, streams or any other place, from where it 15 is desired that the water be elevated to a higher level, for consumption purposes.

Another purpose consists in the provision of an apparatus of this character, wherein means is afforded, whereby as long as the 20 stop cock or faucet on the main line is open, the liquid may continuously flow, as it is the aim that the air pressure, shall at all times be applied, thereby making it possible for the liquid to be drawn from 25 the faucet when needed.

The present apparatus may also be used for the purpose of draining lands, transferring the water from the swampy lands to higher lands, or from streams, springs, wells, 30 lakes and the like for irrigation purposes. The sizes of the inlet and outlet pipes may govern the volume of water to be handled, therefore it is the aim to utilize any diameter of pipes.

35 In connection with the present apparatus compressed air as a motive power is to be used, such air to be supplied by any suitable or convenient means or method, preferably by means of storage tanks, containing air under pressure. In this connection a suitable equalizing valve is designed for placement between such tank or tanks and the apparatus, so that a uniform pressure may be maintained.

40 In order that the equalizing valve may maintain a uniform pressure, a piston valve is employed, in order to prevent friction, the air under pressure being allowed to enter each end of the piston valve casing, 45 imparting reciprocating motions to the piston valve, thereby causing the intake and the exhaust of the air under pressure. Up-

on the intake of the air into the opened port it is the design to impart downward travel to floats in water chambers alternately, thereby expelling or forcing the water from the chambers into the main service line, whereas the exhaust of the utilized air permits the cylinders or chambers to automatically refill alternately. 55 60

A still further purpose involves the provision of means operatively connecting between the floats of said chambers and the reciprocating piston valve, so as to reciprocate the valve, for exhausting the air, and 65 permitting the intake of air under pressure, it being obvious that the intake of air also assists in moving the valve.

The invention still further embodies the provision of means to avoid excessive leakage at the point where the piston valve operates through the piston valve casing, in order to cooperate with the walking beam, which shifts the valve back and forth. 70

The present disclosure in the accompanying drawings is merely illustrative of the general construction and mode of operation of the improved automatic water elevating apparatus, therefore it is obvious when reducing the apparatus to a more practical 75 form for commercial purposes, the invention may be susceptible to changes comprehended within the scope of what is claimed.

The invention comprises further features and combination of parts, as will be herein- 80 after set forth, shown in the drawings and 85 claimed.

In the drawings:

Figure 1 is a vertical sectional view through a well, showing the improved apparatus for automatically elevating the water therefrom, as mounted therein, and constructed in accordance with the invention. 90

Figure 2 is a vertical sectional view through the water elevating apparatus. 95

Figure 3 is a plan view of the same.

Figure 4 is a vertical sectional view at right angles to and on line 4-4 of Figure 2.

Referring to the drawings, 1 designates a well, from which in the present instance, 100 water is designed to be elevated by means of the apparatus herein shown and described. The water elevating apparatus comprises cylinders 2 and 3, which are

threaded or otherwise connected to the upper and lower head flanges 4 and 5. Opposing the head flanges 4 and 5 are head plates 6 and 7, which bridge from one cylinder to the other.

Connected to the lower head plate 7 are the water intake pipes 8, which extend downwardly and upwardly to points level with the upper head plate, and terminate in return bends 9. The terminals of the return bends 9 are provided with cone screens 10. It is the purpose to place the device on the bottoms of wells, or on the bottoms of other bodies of water, and as there is sand and other undesirable foreign matter at the bottom of the water, the cone screens act to prevent the intake of sand and foreign matter. It is obvious that this apparatus may be constructed, in order to be used in wells or other places, and suitable to accommodate any level of water.

Also connected to the lower head plates 7 and communicating with the chambers or the cylinders 2 and 3 are outlet pipes 11. These outlet pipes connect to a T-union 12, from which a main line 13 extends. This line may extend to any suitable location and may unite with a plurality of branches, it being obvious that each branch (not shown) may include valves (not shown) for the purpose of controlling the flow of the water, while the main pipe 13 may have a controlling valve 14, so that the supply of water to all the branches may be cut off or turned on. It is obvious that if any one of the valves of the branches is open, or the valve 14 of the main branch is open, the water is allowed to flow, since the apparatus is automatic throughout its operation.

The intake pipes 8 immediately adjacent to the lower head plate 7, though they may be otherwise located, are provided with check valves 15, which operate automatically to permit the intake of water into the chambers of the cylinders 2 and 3 on the upward stroke of the floats, and to close on the downward movements of the floats, and when pressure enters the chambers of the cylinders.

The outlet pipes 11 have check valves 16, which automatically open on the down stroke of the floats and the intake of air pressure in the upper part of the chambers of the cylinders, to permit the discharge of the water, and close on the upward movements of the floats.

The head plates 6 and 7 are bolted to the head flanges 4 and 5 by means of the bolts 17, and bolted upon the upper head plate 6 by means of the bolts 18 is a plate 19, which constitutes a base for the standard 20 of the piston valve case 21.

The piston valve casing 21 has a valve chamber 22, in which a piston valve 23 is mounted for reciprocating movement. This

piston valve is constructed preferably as shown, though it is obvious that it may be otherwise formed.

The valve casing 21 is cylindrical in form and open ended, and receives a perfectly cylindrical piston valve. This valve is ground into a perfect seat in the chamber 22 of the casing 21, and upon this construction depends the success and proper operation of the apparatus. The open ends of the valve casing 21 are closed by the plates 24, which are fastened to the margin of the ends of the valve casing by means of a suitable number of cap screws or studs 25. With this particular construction, it is the aim to provide an apparatus of this kind to withstand a reasonable amount of air pressure, it being the purpose to use the apparatus for heavy work, where two hundred to over four hundred pounds of air pressure is obtainable.

Air intake pipes 26 are connected to the opposite end plates 24 of the piston valve casing 21, and are designed to be supplied with air under pressure from any suitable source, (not shown), preferably tanks. This supply of air is automatic and constant, so as to enter the chamber 22, and thence the chambers 27 and 28 of the cylinders 2 and 3. The piston valve 23 is provided with exhaust ports 29, which are designed to register alternately with the ports 30 and 31, with which passages 32 and 33 connect. These passages 32 and 33 extend through the standard 20, and connect with the passages 34 and 35 of the head plate 26. The passages 34 and 35 in turn communicate with the chambers 27 and 28 of the cylinders 2 and 3.

The lower part of the valve casing 21 has a slot or opening 36, through which the female member 37 of the universal or ball and socket joint passes. This female member or leg 37 is constructed separate from the valve 23, and is attached thereto by a threaded extension 37a. In other words this female member or leg 37 is screwed into the valve 23, making the same adjustable after the valve has been ground to its seat. Furthermore, the valve 23 is constructed, whereby it may slide upon or engage the entire circumference of the seat or chamber 22. The leg 37 is coupled or connected to the arm 42 of the walking beam 43 by means of a universal or ball and socket joint, which comprises a cavity 40 formed in the female member or leg 37, and the head 41, which is carried by the arm 42. By means of this universal or ball and socket joint friction is reduced to a minimum. The piston valve 23 engages the entire circumferential seat or surface of the chamber 22, and its ports 29 are arranged, one on each side of the female member or leg 37, in order to secure an air tight work-

ing valve, and also to provide a relatively short valve, in order to prevent friction as much as possible, as the air pressure acts on the ends of the valve 1, otherwise the valve 5 could not act as a piston valve. When the piston valve is in the position shown in Figure 2, one of the ports 29 registers with the port 30 and one end of the slot 36, allowing the utilized air to exhaust. When 10 the piston valve assumes a position so that the port 30 communicates with the pipe 26 on the right hand side, the other exhaust port 29 communicates with the port 31 and the other end of the slot 36, allowing the 15 exhaust of utilized air from the chamber 28. The exhaust of utilized air from the chambers 27 and 28 alternately occurs, as the piston valve shifts. A walking beam 43 is pivoted at 44 on one face of the stand- 20 ard 20. It is obvious that when the walking beam is oscillated, the arm 42 tilts, which in turn imparts a reciprocating movement to the piston valve.

Mounted in guides 45 of the plate 19 and 25 passing through the packing glands 46 are rods 27 and 28, the upper ends of which are connected at 49 to the opposite ends of the walking beam 43. Suitable floats 50 are mounted for vertical reciprocating movement in the chambers 27 and 28 of the cylinders 2 and 3, and are guided upon the rods 47 and 48, there being openings 51, through which the rods pass. The upper parts of the rods 47 and 48 have abutment 30 plates 52 and 53, while the lower ends of the rods have abutment plates 54 and 55.

Thus it will be noted that when any one 40 of the faucets of the branch pipes (not shown), are turned on, or when the faucet or valve of the main pipe 13 is turned on, provided the branch pipes are not used, water enters one or the other of the cylinders 2 and 3, it depending on the position of the floats. For example supposing 45 the float of the chamber 50 is in a raised position, and the piston valve 23 is disposed as shown in Figure 2, air under pressure will enter the chamber 22 pass through the passages 35 and into the upper part of the chamber 28. The float in the chamber 50 will move downwardly owing to the pressure of air, expelling the water, as it is needed. When the chamber 28 becomes 55 emptied, the float therein having lowered until it contacts with the abutment plate 55, the rod 48 is moved downwardly, which will impart an oscillatory movement to the walking beam 43, and through its operative arm connection 42 with the piston valve, 60 the piston valve may be shifted to a position, to permit air under pressure to pass through the other passage 34, at the same time putting the first passage 35 in communication with the exhaust pipe 29. Air 65 will then enter the passage 34 on the right,

and owing to the float 50 in the chamber 27 having been raised, the air would impart a downward movement thereon, and cause the expulsion of the water. When the float 50 in the chamber 27 reaches its lowered 70 position, it will contact with the abutment plate 54, and impart a downward movement on the rod 48, which will oscillate the walking beam 43 in the other direction, to assume a position as in Figure 2, allowing 75 the air under pressure to again operate in the chamber 28.

It is obvious that when the floats 50 alternately raise, they will contact with the other respective abutment plates, and thereby shift or oscillate the walking beam so as to close off the exhaust of the utilized compressed air, and shift the piston valve, so as to permit the intake of compressed air 80 on its other end, and vice versa. 85

It is obvious that the standard 20 may be any suitable height upwardly from the base plate 19, so that the piston valve casting 21 may be either located down in the shaft of the well, or any other place, at 90 a point a little above the level of the water, or it may be located at a point above the surface of the shaft of the well, or otherwise disposed with relation to the cylinders. Furthermore the cylinders may or may not 95 rest upon the bottom of the well, but in all instances the level of the water is designed to be at a relatively substantial distance above the upper portions of the cylinders, as disclosed in the drawings. 100

The invention having been set forth, what is claimed as being useful is:

In an apparatus for the purpose indicated, a pair of upright cylinders to be submerged into a body of water, a head plate connecting and closing the upper ends of both cylinders, a standard rising from the head plate and terminating at its upper end in a valve casing disposed horizontally in a direction above the center of the head plate, said standard having passages communicating with the cylinders and having ports communicating with the valve casing, a walking beam operatively fulcrumed upon the standard directly below the center 105 of the valve casing, the lower portion of the valve casing having a slot, a piston slide valve in the valve casing and provided with passages to operatively and alternately connect first one and then the other of said 110 ports with the slot, said slide valve having means engaging through the slot and operatively connecting with the central portion of the walking beam, means for permitting air under pressure to enter the opposite ends 115 of the valve casing, to be controlled by the valve whereby it may enter first one and then the other of the passages through the standard, reciprocating guide rods depending 120 from the opposite ends of the walk- 125

ing beam and passing centrally through the cylinders and provided with upper and lower abutments, floats upon said guide rods to ascend and descend alternately and cooperating with said abutments for tilting the walking beam for shifting the piston slide valve, means for permitting water to enter

the cylinders on the upward strokes of the floats, and means for permitting of the discharge of water on the downward strokes of the floats.

In testimony whereof I hereunto affix my signature.

JAMES D. FOSTER.
